UNITED STATES PATENT OFFICE.

FRANK S. HILLHOUSE, OF KALAMAZOO, MICHIGAN.

POCKET GUIDE AND COMPASS.

SPECIFICATION forming part of Letters Patent No. 512,882, dated January 16, 1894.

Application filed March 2, 1893. Serial No. 464,309. (No model.)

To all whom it may concern:

Be it known that I, FRANK S. HILLHOUSE, a citizen of the United States, residing at Kalamazoo, county of Kalamazoo, State of Michigan, have invented a new and useful 5 Pocket Guide and Compass, of which the following is a specification.

The object of this invention is to produce a new article of manufacture, in which are 10 combined a number of features in a convenient manner for carrying and for reference, all of especial use to the tourist.

To this end the invention in general consists of a folding book-like cover, containing 15 a compass, blank and printed leaves, a map, and if desired a slatted surface.

In the drawings forming a part of this specification, Figure 1 is a perspective view, showing the guide open; and Fig. 2 is an edge 20 view, showing the guide closed.

Referring to the lettered parts of the drawings, A is a cover, made to open and close like a book cover. On the inside of one of the covers and at one end thereof, is a compass, B, fitted into a pocket in the raised portion, C. Of course the raised portion C may be dispensed with, but it has a use, however, below described. Below the compass is a 25 surface, D, upon which dates and memoranda can be temporarily entered by the tourist, which surface for convenience of description we will call a slate, meaning thereby that any slatted surface or its equivalent may be employed for temporary use.

At E are blank and printed pages, the 30 printed matter, for instance, consisting of information in relation to routes, points of interest, time tables, directories, &c., and the blank pages being for the use of the tourist 35 in making a record of any matter which he may desire, more especially a permanent record. The guide may be made, however, without the blank pages.

The cover also contains a map, F, of any 40 particular locality or country to which the guide relates in given instances, such, for an illustration, as the World's Fair grounds at Chicago. This map is preferably made so as to fold in the space between the covers below 45 the raised portion, C, which contains the compass, and the printed and blank pages are

also preferably adapted to fit in said space, so that when the map is folded and the covers closed, the entire space between the covers will be filled, as in Fig. 2, by which means 55 the covers will remain in a neat and unbroken condition, and the raised portion C will not only form a support for the compass but will serve as a guard for the same.

The design in the manufacture of these 60 pocket guides is to make them for different States, localities and even countries, as the case may be, so that tourists can avail themselves of whichever they may desire.

While the slatted surface D, referred to, is 65 deemed especially important for temporary entries, still it may be dispensed with.

Such a pocket guide, containing these necessary and relative features in a compact and handy form, will not only be found convenient 70 to the tourist when traveling, but will constitute an interesting souvenir for preserving afterward and more especially if permanent records have been made of matters of especial interest during the trip. 75

Having thus described my invention, what I claim as new, and desire to secure by Letters Patent of the United States, is—

1. As a new article of manufacture, a pocket guide and compass comprising a folding 80 cover, a raised portion on the inside of one of the covers, a compass fixed in said raised portion, and printed and blank pages and a map in the space between the covers not occupied by said raised portion; substantially 85 as set forth.

2. As a new article of manufacture, a pocket guide and compass comprising a folding cover, a raised portion on the inside of one of the covers, a compass fixed in said raised 90 portion, and a slatted surface, printed and blank pages and a map in the space between the covers not occupied by said raised portion; substantially as set forth.

In testimony to the foregoing I have here- 95 unto subscribed my name in the presence of two witnesses.

FRANK S. HILLHOUSE.
